(57) **CLAIM**

The ornamental design for a BASKETBALL HOOP SUPPORT as shown and described.

DESCRIPTION

FIG. 1 is a perspective view of a BASKETBALL HOOP SUPPORT showing the claimed design;

FIG. 2 is a perspective view thereof;

FIG. 3 is a right-side view thereof;

FIG. 4 is a left-side view thereof;

FIG. 5 is a back view thereof;

FIG. 6 is a front view thereof;

FIG. 7 is a top view thereof;

FIG. 8 is a bottom view thereof.

The even length dash lines, in FIGS. 2-8, depict portions of the BASKETBALL HOOP SUPPORT that form no part of the claimed design and the dash-dot broken lines, in FIG. 1, illustrate environmental structure and form no part of the claimed design.

1 Claim, 8 Drawing Sheets
